CARRYING AND SUPPORTING APPARATUS

Edward M. Cumings, Flint, Mich.

Application January 11, 1934, Serial No. 706,272

3 Claims. (Cl. 224—7)

This invention relates to a carrying and supporting apparatus for use by sportsmen, and particularly designed for use by fishermen.

It is an object of this apparatus to provide a means for carrying various accessories and for supporting accessory portions of the sportsman's clothing during the time that he is engaged in the sport. It is an object of this invention to so distribute the weight of the apparatus and the articles being supported and carried that they will rest in the easiest possible manner upon the wearer and permit him to have the greatest freedom of movement. It is a further object to so arrange the various carrying and supporting parts that they will not interfere with each other nor obstruct each other's use.

It is an object of this invention to provide a means whereby a game receptacle may be carried in alternative positions, and to provide a means for preventing the carrier from sagging in either of the alternate positions. It is an object that this carrying and supporting structure shall provide a compartment adapted to keep certain articles such as cigarettes and matches for instance from moisture, and that this compartment shall be so positioned as to be least likely to come in contact with the moisture.

It is an object also to provide a means for suspending a landing net or the like in the carrying and supporting structure in such a manner that it will not interfere with access to the carrying portion of the apparatus, nor will it be interfered with by that portion, and that the means for suspending the landing net shall be of such nature as to enable the net to be used without being detached from the carrying and supporting structure.

It is an object to provide a plurality of compartments in which articles of various sizes may be carried, and to arrange these compartments in such manner that they will not interfere the one with the other, and so that they will distribute the weight of the articles being carried in such a manner as to be the least burden on the wearer.

With the above and other objects in view, one embodiment of this invention is as illustrated in the accompanying drawings and set forth in the following description by way of example.

50. In the drawings:

Figure 1 is a front elevation of the apparatus constructed in accordance with this invention.

Figure 2 is a rear elevation of the same.

Figure 3 is a section taken along the line 3—3 of Figure 1.

Figure 4 is a section taken along the line 4—4 of Figure 1.

Figure 5 is a section taken along the line 5—5 of Figure 4.

Figure 6 is an enlarged view illustrating a detail of the supporting structure inside of the apparatus.

Figure 7 is a front view illustrating the apparatus in place on the body of a wearer, with various articles being carried thereby.

As illustrated in the drawings, this invention includes a split-skirt structure, an upper non-elastic suspension structure, an inner lower resilient suspension means, and an outer lower non-elastic suspension means.

The split skirt structure includes a series of apron-like sections constituting carriers and a waist belt element having the upper portions of said sections secured thereto. The skirt sections are free of connection to each other from their lower ends to the bottom edge of the belt.

The belt element, indicated at 1, of the skirt structure, is preferably composed of a relatively stiff heavy material such as a heavy fabric. The element 1 may be fastened at the front by any convenient means such as a strap 2 secured to one end of the element 1 by means of rivets 3 or the like and a buckle 4 adapted to engage the hole 5 in the strap 2 secured to the other end of the element 1. There are four skirt sections 6, a front section 7, a short side section 8, and the rear section 9. The sections 6 and 7 are arranged on opposite sides of the front of element 1 when it is in closed position as indicated in Figure 1, the section 6 also at one side of element 1, and the said sections 6, 7 are secured at their upper ends to element 1 by means of stitching 10 or the like. The section 8 is somewhat shorter than the other sections and is disposed over one hip, being secured to the belt along its upper edge in the same manner as the sections 6 and 7. The front carrier section 6 extends around the side and rearwardly substantially to one end of the section 9. This rear section extends across the rear of the device and is secured to element 1 in the manner previously indicated with reference to the other sections.

Secured to the belt adjacent the front ends thereof by means of stitching 11 or the like, and to the rear of element 1 by similar stitching 12 or the like are the right and left suspenders 13 and 14 respectively forming elements of the non-elastic suspension structure. These suspenders are positioned to extend over the respective

shoulders of the wearer, and for the purpose of holding them in proper position there is provided a cross member 15 across the shoulder portion at the rear, this shoulder member being secured to the shoulder straps by means of stitching 16.

5 Beneath each strap at the position where it is adapted to rest against the top of the wearer's shoulder there is provided a shoulder piece, these being numbered 17 and 18 respectively. The 10 shoulder pieces are formed of relatively stiff heavy material preferably somewhat heavier than either the belt or the shoulder straps, so that the shoulder straps will be prevented from cutting into or otherwise injuring the shoulder of the 15 wearer. These shoulder pieces may be secured in place beneath the shoulder straps by means of stitching 19 or the like. On the front portion of these shoulder straps there may be provided an attaching ring 20 secured in place by means of a short length of strap 21 riveted to the shoulder strap 13 or 14 as at 22. Any necessary small articles may be tied to or otherwise suspended from these rings 20.

Secured to element 1 at the lower ends of one 25 of the shoulder straps, preferably the left shoulder strap 14, there are a pair of attaching rings 23 similar to the attaching rings 20 and secured in place on the outer face of element 1 by means of short straps 24 and rivets 25. The purpose of these rings 23 is to detachably receive the snap 30 fasteners 26 on the ends of the strap 27. This strap member 27 is made in two parts joined together at approximately the center of the strap member by means of a buckle 28 permanently secured to one portion and detachably secured to the other portion. This strap member as illustrated in Figure 7 of the drawings is for the purpose of supporting a creel 29 provided with a lid 30 hinged thereto in the customary manner, 35 or to carry any other game receptacle which may be found convenient. The rings 23 and strap member 27 provide the outer lower non-elastic suspension means.

The position of the creel as illustrated in Figure 7 is over the hip of the wearer and is the natural position for the creel to assume when the strap member 27 is secured to the attaching rings 23. However, many sportsmen prefer to have the creel or other game receptacle positioned further to the rear. In order to make this possible, there are provided alternative or optional attaching rings 31 secured to the belt at the lower end of the shoulder strap 13 on the outer surface of element 1, and secured to element 1 to the left of the lower front end of the shoulder strap 14. These attaching rings are secured to element 1 by means of short straps 32 and rivets 33 in much the same manner as the attaching rings 20 and 23. It will be seen that when the strap member 27 is secured to the attaching rings 31 instead of to the attaching rings 23, the position of the creel or other game receptacle will be changed from that illustrated in Figure 7 to a position more in the rear of the wearer. In this position, however, it is noted that the forward attaching ring 31 is at a point spaced a considerable distance from the lower front end of the shoulder strap 14. The non-elastic upper suspension structure not only includes the suspenders 13, 14 but also includes an auxiliary suspender or supporting strap for a purpose now to be described. In order to prevent any sagging of element 1 at the point where this forward ring 31 is attached, there is provided an auxiliary supporting strap 34 secured to the

shoulder strap 14 at its upper end substantially at the forward extremity of the shoulder piece 18 by means of stitching 35. At its lower end, this auxiliary supporting strap 34 is secured to the inside face of element 1 substantially at the point where the forward attaching ring 31 is connected, by means of stitching 36 or the like. This, it will be seen, will positively support the carrier apparatus at the point where the ring 31 would exert its pull, and would prevent any sagging of the ring 31 at that point when the game receptacle 29 is secured to the ring 31.

The construction of the inner lower resilient suspension means will now be referred to. Secured to the inner surface of element 1 substantially at each of the lower ends of the right shoulder strap 13 there is an attaching ring 37. These attaching rings 37 are secured by means of short straps 38 and rivets 39 in the manner above set forth. These attaching rings 37 are for the purpose of detachably receiving the snap fasteners 40 carried on the opposite ends of the elastic member 41. These snap fasteners are provided in the usual manner with ring portions 42 adapted to receive an end of the extensible member 25 and the ends of this extensible or elastic member are secured through the rings 42 by means of fastening elements 43 forming loops at the ends of the elastic element. Intermediate its ends, this elastic element is provided with a third snap 30 fastener 44. The elastic member is merely passed through the ring 45 of this snap fastener so that the same will be slidably mounted on the elastic member. The purpose of this elastic member and the snap fastener slidably mounted intermediate its ends is for the suspension of a landing net 46 or the like having its handle 47 provided with suitable means to which the snap fastener 44 may be attached.

Secured to the inner face of element 1 by means 40 of rivets 48 or the like substantially at the lower rear ends of the respective shoulder straps there is a pair of short strap members 49 adapted to serve as supporters for the rear portion of a pair of waders or the like. Each of these strap members 49 is formed with a plurality of buttonholes 50 adapted to adjustably receive the buttons usually provided upon the rear of the waders for supporting the same.

Secured to the front ends of each of the shoulder pieces 17 and 18 and extending downwardly therefrom inside of element 1 and carrier apparatus are a pair of supporting straps 51. These straps 51 are secured between the shoulder straps and the shoulder pieces in any convenient manner and are provided at their lower ends with openings 52 adapted to cooperate with buckles 53 for the purpose of securing the suspenders 54 to the lower ends of the strap 51. It will be seen that each of the suspenders 54 consists of two 60 strap portions extending downwardly at an angle to each other, and each of these portions being provided with an opening 55 adjacent the lower end thereof for the purpose of receiving the supporting buttons customarily provided upon the front of waders or the like.

Referring back now to the skirt sections mentioned, reference is first had to the right front section 6. By reference to Figure 5, it will be seen that this section consists of a rear wall 56 70 and of a front wall 57 secured to the rear wall 56 at the lower edge 58. These front and rear walls 56 and 57 are secured together at their opposite ends by means of stitching 59, and up through their central portions by means of stitching 60 so 75

as to form a pair of pockets side by side of substantially equal size. It is noted that this apron-like section is positioned substantially over the point where the landing net 46 would be secured to the elastic element 41. It is a matter of note, however, that this elastic element is positioned beneath or within the interior of the carrier apparatus so that it will not interfere with the pockets of the section 6 nor obstruct access thereto. However, when the net 46 is in use it is apparent that the section 6 will be pulled outwardly and articles within the pockets of this section and particularly within the pocket at the rearward end thereof would tend to be thrown out. For the purpose of preventing this from occurring, this pocket is provided with a flap 61 adapted to close the same. In order to provide space for additional small articles, the flap 61 has a separate member 62 secured to the front face thereof at 63 so as to form a pair of pockets 64 and 65 respectively within the flap member 61. Within the pocket at the forward end of this section there is provided an intermediate wall 66 secured to the rear wall 56 in such a manner as to form two small pockets 67 and 68 respectively. A long narrow pocket is secured in a substantially upright position at 69 on the front surface of this carrier section.

With reference to the skirt section 7, this section is likewise formed with a rear or inner wall 69' and an outer wall 70 secured together at 71 to form a pocket between. It is noted, however, that this pocket would fall beneath the position of the strap member 27 so that it would be difficult to provide a flap therefor which could be opened when the strap member 27 is in position. In order to overcome this difficulty, there has been formed a flap of triangular shape as illustrated at 72 so that it may be opened without substantial interference from the strap member 27. Likewise, the shape of this flap member 72 permits of access to the substantial upright elongated pocket 73 secured to the front wall of this skirt section 7.

With reference to the skirt section 8, it is noted in Figure 5 that this section consists not only of the rear wall 74 and the front wall 75 and the flap 76 for closing the same, but that each of these walls is provided with a lining 77 of rubberized silk or other moisture-proof material. In addition, it is noted that this pocket or skirt section is made somewhat shorter than the other skirt sections and is positioned above the position of a creel attached to the front member 27. Thus, by virtue of its position above the creel, it will be further protected from the moisture when the sportsman is wading in a stream or the like. This pocket is for the purpose of keeping any articles which might be desired moisture-free such as for instance tobacco, matches, etc.

The rear skirt section of this apparatus consists as illustrated in Figure 4 of an inner wall 78 and an outer wall 79. These inner and outer walls are joined together by means of accordion-pleating sides and bottom 80 so that this carrier section may be made of use in carrying the somewhat bulky as well as heavy articles. This pocket may be closed by means of a flap 81 and a suitable button or the like 82. It is noted that the position of this skirt section upon the wearer's body and with respect to the other portions of the carrying and supporting apparatus is such that the maximum weight can be carried in this section. It is well known that in a device of this general type a much greater weight may be car-

ried upon the back of the wearer than on portions of the apparatus in front of him.

As for element 1, it is particularly noteworthy that as illustrated in the drawings it consists of the relatively heavy and stiff belt member 83 which is positioned adjacent the wearer's body, and of the relatively flexible member 84 secured to the outer face thereof. It is to be noted that the upper and lower edges of the member 84 are folded upon themselves before they are stitched to the member 83. The lower ends of the shoulder straps and of the auxiliary supporting strap 34 are inserted between these two members before they are secured together by means such as the stitching 85. At their lower edges, these two belt members receive the upper edges of the carrier sections between them and they are then secured together by means of stitching such as 86.

From the foregoing description it will be appreciated that a very advantageous carrying and supporting apparatus has been provided by this invention. First of all, there is the split-skirt structure comprising the belt and the various sections, the pockets in the various sections themselves being so arranged as to properly distribute the load upon the wearer and upon the said structure and so as not to interfere with the other parts of the apparatus. Then the shoulder straps are provided and are formed in such a manner as to bear most easily upon the shoulders of the wearer and to support element 1 at five points, two at its back and three at its front. The points at the back and the points at the front substantially equally spaced from each other. Means is provided for supporting the creel or other game receptacle in optional positions depending upon the desires of the sportsman, and provision is made for preventing the sagging of element 1 when the creel is secured in one of its optional positions, in which position it would have caused sagging were it not for the provision made by this invention. In addition to the above, this invention provides a device whereby a landing net or the like may be suspended from the split-skirt structure in a position where it will be out of the wearer's way and will not interfere in any way with or obstruct access to the pockets of the carrier member, but in which the landing net will be brought into instant use without the necessity for detaching it from the split-skirt structure and without interference with the other portions of the split-skirt structure. The apparatus also supplies a supporting means for waders or the like, which supporting means are positioned so as not to interfere with or obstruct access to the pockets or other portions of the split-skirt structure, and yet which are so positioned as to transmit the strain and stress placed upon them in a most direct manner to the shoulders of the wearer.

It is to be understood that the foregoing is by way of illustration and example only and is not to be taken as in any way limiting the spirit or the scope of this invention. Such limitation is to be by the prior art and by the terms of the appended claims only.

What I claim is:—

1. In a carrying and supporting apparatus adapted to be worn by a fisherman, a split-skirt structure formed of a belt element for encompassing the waist of the wearer, a combined front and side section for opposing one side and a part of the front of the wearer below said element, a front section for opposing the remaining

- part of the front of the wearer below said element, a side section for opposing the other side of the wearer below said element, a back section for opposing the back of the wearer below said element, said sections having their upper portions extended into the lower portion of said belt element from the bottom edge of the latter and means for securing the lower portion of the belt element and the upper portions of said sections together, said sections being free of connection throughout from the bottom edge of said element to the lower ends thereof, each of said sections being formed with means to constitute a carrier, and a shoulder suspension structure for said split-skirt structure connected at three spaced points to the front and at two spaced points to the back of said element, comprising a bracing strap extending from one of said front spaced points in proximity to the side of the wearer to the suspension structure on the upper front portion thereof.
2. In a carrying and supporting apparatus adapted to be worn by a fisherman, a split-skirt structure formed of a combined front and side section for opposing one side and a part of the front of one side of the body of a wearer below the waist and being provided with a pair of permanently open pockets and a normally closed pocket, a front section for opposing the remaining part of the front of the body of the wearer below the waist and being provided with a normally

closed pocket and a permanently open pocket, a side section for opposing the other side of the body of the wearer below the waist and being provided with a normally closed pocket, a back section for opposing the back of the wearer below the waist and being provided with a normally closed pocket, a belt element for encompassing the waist of the wearer and means for securing the upper portions of said sections to said element, and said sections being free of connection throughout from the bottom edge of said element to the lower ends thereof.

3. In a carrying and supporting apparatus adapted to be worn by a fisherman, a split-skirt structure including a belt having depending therefrom a series of apron-like sections provided with means to form carriers, an upper non-elastic suspension structure anchored to a pair of spaced points of the back and three spaced points of the front of the belt, a depending lower outer non-elastic suspension means, attaching elements connected to the ends of said last means, and a plurality of grouped attaching elements on the outer surface of said belt adapted to be selectively engaged by said first-mentioned attaching elements according to the varying distribution of the load imposed upon said carriers to approximate a desired balance between said load and the load adapted to be carried by said non-elastic suspension means.

EDWARD M. CUMINGS. 30
